ATTORNEY.

UNITED STATES PATENT OFFICE.

CHARLES STRICKRODT, OF NEW YORK, N. Y.

FAN.

SPECIFICATION forming part of Letters Patent No. 252,706, dated January 24, 1882.

Application filed December 10, 1880. (No model.)

To all whom it may concern:

Be it known that I, CHARLES STRICKRODT, of the city, county, and State of New York, have invented certain new and useful Improvements in Fans, of which the following is a specification.

This invention has reference to improvements in that class of fans in which the web is applied by its end folds to handles which are connected at their upper ends to center disks of the web, so as to open or close the web by being swung back to back or face to face.

The invention relates more especially to improvements in the pivoted connection of the handles with the center disks of the web, so that the use of transverse pivot-pins which pass from one disk to the other through the fabric of the web may be done away with, and a simpler and cheaper pivot-connection of the fan-handles be obtained.

The invention consists of the combination of the web with two handles which are pivoted to center disks by means of end caps or mountings that are provided with inwardly-bent lugs having turned-up prongs, said prongs being sprung through holes of the disks equidistantly from the center of the same.

In the accompanying drawings, Figure 1 represents a side view of my improved fan, shown in closed position. Fig. 2 is a detail top view of the same, and Fig. 3 is a detail view of the blank from which the end cap or mounting of the handles is made.

Similar letters of reference indicate corresponding parts.

In the drawings, A represents the web, and B B the handles, of my improved fan. The end folds of the web A are attached in the usual manner to the inside of the handles B, the handles being applied at their upper ends to center disks, C, which cover the connection of the handle ends with the web. The handles B are pivoted to the center disks, C, by means of end caps or mountings, D, which are arranged with lower fastening-lugs, a, and with upper connecting-lugs, b. The lower side lugs, a, as well as an end lug, d, serve for attaching

the cap or mounting D to the end of the handle, while the upper lugs, b, are bent inwardly at right angles to the main portion of the cap, 50 and serve to establish the pivotal connection with the disks by means of one or more prongs, b'. These prongs are stamped up from the body of the upper side lugs, a, sprung through holes which are equidistantly from the center of the disks C, and then bent over on the outside of the same, so as to form a simple and reliable pivot-connection therewith. By thus connecting the handles with the disks not only the transverse pivot-pins, which heretofore had to be forced through the web of the fan, and which frequently played loose from the disks, can be dispensed with, but also a simpler, cheaper, and better fan of the class described obtained. 65

I desire it to be distinctly understood that I lay no claim, broadly, to the pivot-connection between the handles and center links, as they are well known, the essential feature of my invention being the connection of the end caps 70 of the handles by means of pronged side lugs with the perforated center disks of the fan.

Having thus described my invention, I claim as new and desire to secure by Letters Patent—

1. The combination, with the web A and 75 handles B B of a fan, the latter being provided with end caps or mountings, D, having inwardly-bent and pronged lugs, of center disks, C, having holes equidistantly from the center, through which the prong or prongs are sprung, 80 substantially as and for the purpose set forth.

2. An end cap or mounting for fans, having lower fastening side lugs, a a, upper side lugs, b b, with one or more bent-up prongs, and an end lug, d, substantially as shown and described. 85

In testimony that I claim the foregoing as my invention I have signed my name, in presence of two witnesses, this 26th day of November, 1880.

CHARLES STRICKRODT.
